CART FOR SPOOLS OF WIRE

John I. Mitchell, Rte. 3, Box 577, Glendale, Ariz. 85301

Filed Jan. 22, 1970, Ser. No. 21,033

Term of patent 14 years

Int. Cl. D12—02

U.S. Cl. D14—3

FIG. 1 is a perspective view of a cart for spools of wire according to my design;

FIG. 2 is a side elevational view thereof, the elevational view of the opposite side being the reverse of this view;

FIG. 3 is a top plan view of this cart; and

FIG. 4 is an end elevational view of the cart showing my design.

I claim:

The ornamental design for cart for spools of wire, substantially as shown and described.
